UNITED STATES PATENT OFFICE.

WILLIAM H. GRAHAM, OF ST. LOUIS, MISSOURI.

IMPROVEMENT IN DOMESTIC BOILERS.

Specification forming part of Letters Patent No. 151,968, dated June 16, 1874; application filed April 28, 1874.

To all whom it may concern:

Be it known that I, WILLIAM H. GRAHAM, of St. Louis, county of St. Louis and State of Missouri, have invented an Improved Kitchen-Boiler, of which the following is a specification:

This invention relates chiefly to the combination of the parts constituting the bottom of the boiler, and by means whereof new and important advantages are achieved, as will hereinafter appear.

Of the drawing, Figure 1 is a sectional elevation; Fig. 2, a side elevation.

A is the boiler. The ordinary construction of the boiler A has a flat or slightly-curved bottom, which permits the accumulation of mud, sediment, &c., at bottom, and the formation of encrustation inside of boiler, all of which it is difficult to remove from said boiler, as well as rendering the same and its pipe attachments ineffectual of operation. Also, a boiler of the ordinary construction is difficult of securing in a plumb vertical position, providing it with a rest or stand, and otherwise necessitates frequent changes, repairs, and cleaning, involving extra time, labor, and expense. All this to avoid, I provide the boiler A and form its bottom B cone-shaped, as indicated in figures. To secure the cone-shaped bottom B to boiler, the latter has its bottom edge a united to the annular flange b of the former by rivets, &c. (See figures.) Further, my bottom B has a flattened annular rest, b', (see Fig. 1,) for the better supporting and securing of the boiler to suitable legs, or to a stand. A firm and plumb position of the boiler can thus be had. The bottom B forms a settling-chamber for the accumulations and settling of the mud, sediment, &c., and in order to remove which I provide said bottom with a screw-cap, C. The screw-cap C is connected to the threaded opening of the bottom, and said cap can readily be removed, and thus an easy entrance through and inside the bottom B can be had, to effect the inside cleaning and removal of sedimentary deposits that otherwise do not pass out of waste-pipe. c is the waste-pipe. This connects the screw-cap C. Whenever waste, therefore, does not pass

out of the pipe c, or the pipe becomes choked, it is only necessary to unscrew said pipe by removing the cap C, and the enlarged opening presented will readily permit the operator to reach the inside of boiler and its bottom to remedy the difficulty aforesaid. I provide a feed-pipe, D, from boiler to heater or range, and said pipe I arrange to pass through the bottom B, and project above the mud-line in boiler, as shown in Fig. 1. The purer water is thus insured to pass from boiler to said heater or range, the sedimentary matter being below in the settling-chamber of the bottom B. At the top the boiler A is closed by the top E, which is similarly riveted by its flange e to the flange e' of the boiler. (See Fig. 1.) Through the top E passes the cold-water feed-pipe F. This, at its lower end, has a perforated globe or rose, f, which is for the purpose of spraying the water above the mud-line, cleaning the sides of boiler, it being my object to prevent the direct discharge with force of the water into the bottom, and consequently avoid the scattering of the deposits in said bottom.

My discharge, as here shown, washes whatever deposits gather around the sides of boiler into the settling-chamber. Also, through top E of boiler passes the hot-water feed-pipe G, both said pipes F and G being made to connect with water-sink or place of usage, as ordinarily. The pipes F and G can have stop-cocks, as usual.

What I claim is—

1. The combination of the bottom B, boiler A, and feed-pipe F, having globe f, to operate as and for the purpose set forth.

2. The combination of the bottom B, its screw-cap C, flange b, annular rest b', boiler A, having pipes c D F G, and globe f, all arranged to operate as herein shown and described.

In testimony of said invention I have hereunto set my hand in presence of witnesses.

WILLIAM H. GRAHAM.
